UNITED STATES PATENT OFFICE.

ALFRED B. REEVES, OF COLUMBUS, INDIANA, ASSIGNOR TO REEVES & CO.,
OF SAME PLACE.

PLOW-GAGE.

SPECIFICATION forming part of Letters Patent No. 340,242, dated April 20, 1886.

Application filed January 18, 1886. Serial No. 188,860. (No model.)

To all whom it may concern:

Be it known that I, ALFRED B. REEVES, a citizen of the United States, residing at Columbus, in the county of Bartholomew and State 5 of Indiana, have invented a new and useful Improvement in Plow-Gages, of which the following is a specification.

My invention relates to an improved gage for plows, of that class which consists of 10 a curved runner hinged at one end to the plow-beam and having the opposite end vertically adjustable relatively thereto, to determine the depth of cut of the shovels of a double shovel plow or like implement.

15 The objects of my improvement are to provide a gage of the class described which shall be light and at the same time sufficiently rigid in its construction to successfully resist the dragging thrust to which such device is necessarily subjected, and which may be easily and quickly attached to or detached from the plow-beam.

The accompanying drawing illustrates my invention.

25 The figure is a perspective view of a double-shovel plow with my improved gage.

The gage is formed of a light flat bar of iron bent a quarter-turn, so as to form the runner *a*, in the upper end of which is formed an eye, 30 *b*. Said runner is stiffened to resist a dragging thrust in the direction of its length by a brace, *c*, formed also of a light flat bar twisted at the ends, so that the wide surfaces of said ends lie in planes parallel, respectively, with 35 the flat surface of the upper and lower ends of

runner *a*, while the middle or principal portion of the brace presents its wider portion in a plane at right angles to said surfaces. The runner is attached to the plow-beam, so as to swing in a vertical plane, by means of a staple, 40 *s*, passing through eye *b* and having its ends secured in the plow-beam.

For the purpose of adjusting the horizontal portions of runner *a* vertically in relation to the points of the plow-shovels *e* and *f*, a straight 45 flat bar, *h*, having a series of holes, *i*, is pivoted at one end to the brace *c* at *j*, and its free end passes upward through a mortise, *m*, in the plow-beam. A pin, *n*, passed through one of the series of holes *i*, determines the relative 50 position of the shovels and runner *a*, the plow-beam resting on said pin and the shovels when at work projecting more or less below the runner. When not at work the runner is adjusted so as to be on a line with or slightly below the 55 points of the shovels, and it then forms a convenient support for the plow when moving from place to place.

I claim as my invention—

The above-described plow-gage consisting of 60 the runner *a*, having eye *b*, staple *s*, brace *c*, adjusting-bar *h*, and pin *n*, all constructed in the manner described, and arranged to co-operate with a plow-beam, as and for the purpose specified.

ALFRED B. REEVES.
